UNITED STATES PATENT OFFICE.

BERNHARD W. WESTBO, OF SOUTH PRAIRIE, WASHINGTON.

LUMBER-LOADING DEVICE.

Application filed June 23, 1924. Serial No. 721,338.

To all whom it may concern:

Be it known that I, BERNHARD W. WESTBO, a citizen of the United States, and a resident of South Prairie, Pierce County, Washington, have invented certain new and useful Improvements in Lumber-Loading Devices, of which the following is a specification.

This invention relates to improvements in lumber loading devices, and particularly to a device of that character especially adapted for the handling of lumber and for loading it into and from ships; the principal object of the invention being to provide such a device in the form of a grapple, adapted to be attached to and lifted by a hoisting cable and which has means provided for embracing and lifting large stacks of lumber.

Another object of the invention is to provide a device as above stated having manually operable means for easily and quickly adjusting the lifting members so as to free the device from a stack of lumber or for securing it to the stack.

A still further object resides in the provision of clamping levers for retaining a load against slippage while being carried.

Other objects reside in the details of construction and combination of parts embodied in the invention and in their mode of operation.

In accomplishing these and other objects of the invention, I have provided the improved details of construction, the preferred forms of which are illustrated in the accompanying drawings, wherein—

Figure 1 is a perspective view illustrating the application of a device embodying the present invention to a stack of lumber.

Figure 2 is an enlarged side view of the device.

Figure 3 is an end view of the same.

Figure 4 is a plan view of the carrier with the lifting arms turned to the position they assume while carrying a load and showing in dotted lines the position to which they are adjusted to free the device from the load.

Figure 5 is a side elevation of a device of a modified construction.

Figure 6 is a plan view of the same.

Referring more in detail to the drawings—

The carrier comprises a horizontally disposed main frame structure comprising two

parallel, spaced apart beams 1 and 2, joined rigidly by a transverse beam 3 that connects at its ends with the central portions of the end beams. This frame can be made in suitable widths and lengths and preferably would be cast in one piece of such strength that a load of considerable weight could be lifted thereby.

At the opposite ends of the end beams 1 and 2, or at what may be termed the four corners of the frame, bearings are provided wherein the upper ends of four vertical posts, or shafts 4, are rotatably held. These are of equal length and at their lower ends have laterally directed arms 5 fixed rigidly thereto and which may be moved to different positions by rotation of the shafts to which they are fixed.

Fixed on the upper ends of the four shafts 4 are crank arms 6 and mounted pivotally on the frame, by pins 7, at opposite ends of the cross beam 3, are bell cranks comprising oppositely extending arms 8 and actuating levers 9. The crank arms 8 of each lever are connected by links 10 with the cranks 6 at that side of the frame to provide connections through which, by movement of the bell crank, both shafts may be simultaneously rotated to swing the arms 5 into or from load carrying position beneath the frame.

Formed centrally on the cross beam 3 are three spaced apart lugs 12 and pivotally mounted between these on a bolt or pin 13 extended through them are two clamping levers 14 that extend toward opposite ends of the frame as shown in Figure 4. The upper ends of these levers extend somewhat past their pivot point and are connected by means of links 15 with a ring 16 to which a hoisting cable 17 may be attached. At their lower ends the levers have cross bars 18 fixed thereto adapted to engage with the load when lifting is done to hold it level and against slippage in either direction.

In preparing lumber to be handled with the present device it is stacked as shown at 19, in Figure 1, upon supporting cleats 20 to hold the stack clear of the ground, and the stack is made of such width that the carrier may be lowered over it. To position the carrier, the shafts 4 are first rotated so that the carrier arms 5 will be swung outwardly, as shown in dotted lines in Figures 1 and 4, so as to clear the stack

when the device is lowered over it. Then, after the carrier has been lowered and positioned properly between the ends of the stack, the shafts are rotated, by the actuation of the bell cranks, to swing the carrier arms inwardly from opposite sides to a position as shown in Figures 3 and 4, to serve as a support for the stack when it is lifted.

- 10 When the device is lifted by upward pull on the cable 17, the cross bars 18 on the lower ends of levers 14 are swung downwardly and clamped tightly against the lumber stack and thereby hold it in balanced 15 position and prevent slippage of the load. When the load is lowered onto a support and the cable slackened, the holding pressure of the levers 14 is removed and the arms 5 may be swung outwardly to free 20 the device so that it may be lifted from the stack.

In Figures 5 and 6, I have illustrated a modification of the device wherein the clamping levers 14 are pivotally fixed between lugs 25 extended from the under side of the cross beam 3 and wherein the crank arms 6 of the four posts 4 are connected by means of links 10 with the opposite ends of cross bars 27 fixed to the ends of a shaft 28 supported parallel with and above the beam 3 in bearings 29-29. The cross bars 27 have extended ends 30 equipped with handles 31 whereby the shaft may be rotated to effect the adjustment of the lifting arm 5, as before described.

It is readily apparent that changes could be made in various details of construction without departing from the spirit of the invention and for this reason I do not wish to 40 be limited only to the details herein illustrated.

Having thus described my invention, what I claim as new therein and desire to secure by Letters-Patent, is:

- 45 1. A device of the class described comprising a horizontal frame structure, a plurality of shafts fixed rotatably at their upper ends in said frame and extending downwardly at opposite sides thereof, load carrying arms fixed perpendicularly to the lower ends of the shafts, means at each side of the frame operable to simultaneously rotate the shafts to swing their arms into or from load carrying position, a pair of 50 clamping levers pivotally attached to the frame having ends adapted to engage a load being lifted and means for connecting their opposite end with a hoisting cable.

2. In a device of the class described, a horizontal frame structure having parallel, opposite side beams and a transverse beam rigidly connecting them at their centers, shafts rotatably fixed at their upper ends in the ends of said side beams and extended downwardly therefrom, arms fixed perpendicularly to the lower ends of the shafts, crank arms fixed to the upper ends of the shafts, bell cranks fixed pivotally to the frame at opposite sides and links connecting the bell cranks with the said crank arms whereby actuation of the bell cranks at either side of the frame causes rotation of the shafts at that side to swing the arms into or from load carrying position and means for attaching a hoisting cable centrally to the frame.

3. In a device of the class described, a horizontal frame structure having parallel, opposite side beams and a transverse beam rigidly connecting them, at their centers, shafts rotatably fixed at their upper ends in the ends of said side beams and extended downwardly therefrom, arms fixed perpendicularly to the lower ends of the shafts, crank arms fixed to the upper ends of the shafts, bell cranks fixed pivotally to the frame at opposite sides and links connecting the bell cranks with the said crank arms whereby actuation of the bell cranks, at either side of the frame, causes rotation of the shafts at that side to swing the arms into or from load carrying position, a pair of levers pivotally fixed centrally to the cross beam of the frame to extend in opposite directions parallel with the side beams, said levers having cross bars at their outer ends for engaging a load carried by the device and having connecting means at their opposite ends for attachment to a hoisting cable.

4. A device of the class described comprising a horizontal frame structure, a plurality of shafts fixed at their upper ends in said frame and extending downwardly therefrom, load carrying arms fixed to the lower ends of the shafts and clamping levers pivotally mounted in the frame having ends adapted for connection with a hoisting means and their opposite ends adapted to be clamped against the top of the load in opposed relation to the said supporting arms when tension is applied to the hoisting means.

Signed at Tacoma, Pierce County, Washington, this 25th day of April 1924.

BERNHARD W. WESTBO.
